(57) CLAIM

The ornamental design for a bench, as shown and described.

DESCRIPTION

FIG. 1 is a front perspective view of a bench showing one embodiment of our new design.

FIG. 2 is a front view thereof, the rear view being symmetrical thereto.

FIG. 3 is a left view thereof, the right view being symmetrical thereto; and,

FIG. 4 is a top view thereof.

The broken lines shown in the figures represent portions of the bench that form no part of the claimed design.

The symbolic break lines in the drawings convey that the appearance of any portion of the bench between the symbolic break lines form no part of the claimed design.
